CARPET.

No. 17,609.

Patented Aug. 9, 1887.

UNITED STATES PATENT OFFICE.

EUGENE H. HILL, OF PHILADELPHIA, PENNSYLVANIA, ASSIGNOR TO SCHOFIELD, MASON & CO., OF SAME PLACE.

DESIGN FOR A CARPET.

SPECIFICATION forming part of Design No. 17,609, dated August 9, 1887.

Application filed July 15, 1887. Serial No. 244,422. Term of patent 3½ years.

To all whom it may concern:

Be it known that I, EUGENE H. HILL, a citizen and resident of the city of Philadelphia, State of Pennsylvania, have invented or produced a new and original Design for a Pattern to be wrought into Body-Brussels and other Carpeting; and I do hereby declare that the photographic illustration accompanying this specification gives and conveys to any one skilled in the art of carpet-weaving a defined and thorough description of the nature of my invention, that is sufficient to enable any one so skilled to use the same.

What I claim as my invention, and desire to secure by Letters Patent, is—

The design for carpets, as shown in the photographic illustration accompanying this specification.
